MATERIAL HANDLING APPARATUS

John D. Russell, Cranberry Township, Venango County, and Henry Thies, Franklin, Pa., assignors to Joy Manufacturing Company, a corporation of Pennsylvania

Application May 22, 1942, Serial No. 444,134

1 Claim. (Cl. 254—88)

This invention relates to material handling apparatus and more particularly to mechanism for elevating or raising a cable drawn vehicle or skip into position to unload directly into a second material transporting device medium.

The present invention is particularly adapted for use in coal mining and especially the thinner seams thereof where the coal is moved from the working face to the primary haulage of the mine in a drag skip or wheeled car which is pulled back and forth by a double-acting drum hoist located adjacent the primary haulage unit.

The primary object of this invention is to provide means for raising or elevating the drag skip or car as it approaches the primary haulage unit whereby the material or coal being transported therein can be discharged directly onto a belt conveyor or other means forming the main haulage unit.

Another object is to provide means for elevating a drag skip or car which is operated by the movement of the skip or car toward the main haulage unit.

A further object is to provide an elevator having a platform for receiving a drag skip or car which is capable of moving forwardly and upwardly to raise the discharge end of the skip or car above the top of a primary transporting unit into which the skip or car is adapted to discharge its load.

A still further object is to provide an elevator for raising a drag skip or car above the surface over which it normally travels which is novel in construction and operation.

These and other objects which will hereinafter be made apparent to those skilled in this particular art are accomplished by means of this invention, one embodiment of which is described in the following specification and illustrated in the accompanying drawings, wherein:

Fig. 1 is a perspective view of a drag skip or car elevator made in accordance with my invention;

Fig. 2 is an enlarged view in side elevation of the elevator having a car positioned thereon and showing the relation of the elevator to the primary haulage unit, in this instance a belt conveyor;

Fig. 3 is an enlarged plan view of the elevator, and

Fig. 4 is an enlarged section taken on line IV—IV of Fig. 3.

Referring to the drawings in detail; 10 represents a car of the drag line type used to transport material in coal mines from the working

face or loading area of the mine to a discharge or unloading station where the coal or other material being transported in the car 10 is discharged onto a primary haulage unit such as a belt conveyor 11. The car 10 is pulled back and forth from the working face or loading area to the discharge station by cables 12 and 13 attached to the forward and rear ends respectively of the car and to a double-acting drum hoist 14 of usual construction which plays out the cable 12 when the cable 13 is being wound on the drum and vice versa. At or near the working face or area, the cable 13 passes around a pulley 14 mounted on a post 15 embedded in the surface 10 on which the car 10 travels so that as the cable 13 is wound on the drum, the car will be hauled from the discharge or unloading station to the working face or loading area.

In order that the car 10, when at the unloading 20 station will be elevated to position the discharge end of the car above the top of the belt conveyor 11 and thereby facilitate the unloading of the car an elevator 17 embodying my invention is positioned adjacent the belt conveyor 11 for receiving the car 10 as it is pulled toward the conveyor 11.

The elevator 17 comprises a rectangular shaped frame 18 having an upright member 19 at each corner thereof. Each of the upright members 30 19 has an upwardly and forwardly sloping cam track 20 formed therein in which a roller 21 is placed for following the contour of the cam track 20. The rollers 21 are journaled on spindles 22 secured to the corners of a car-receiving platform 23. In operation the cables 12 and 13 pass over the platform 23 and in order that the car 10 may be readily pulled onto the platform, the rear edge is beveled as at 24, and outwardly flared side boards 25 of sufficient height to engage the 35 sides of the car are secured to the platform adjacent the beveled edge 24 for guiding and centering the car on the platform.

In operation, the frame 18 of the elevator is positioned adjacent to the side of the conveyor 45 11 so that when the elevator platform 23 is raised the forward or discharge end of the car 10 will extend over the conveyor 11.

Assuming that the car 10 has been loaded and is ready to be hauled to the discharge station, the operator starts the hoist 14 which winds up the cable 12 and plays out the cable 13 hauling the car toward the discharge station. As the car approaches the elevator 17 the sides of the car are engaged by the outwardly flared side boards 25 which guide the car onto the platform

23 and the wheels readily pass up the beveled surface 24. When the car has reached the desired position on the platform 23, the wheels thereof come in contact with stop blocks 26 which limit further forward movement of the car relative to the platform 23 and brings the car to rest on the platform. From this construction it is apparent that continuing to wind up the cable 12 on the hoist 14 will cause the follower rollers 21 to move in the cam tracks 20 and due to the shape of the tracks the platform 23 will be moved forwardly and upwardly, and the discharge end of the car will be positioned over the top of the belt conveyor 11.

After the car 10 has been unloaded, the hoist 14 is reversed which winds up the cable 13 and plays out the cable 12. As the cable 13 starts to wind up, the platform 23 is pulled rearwardly of the frame 18 and the rollers 21 travel rearwardly and downwardly in the cam tracks 20 and return the platform to its original position. Relatively low wheel stops 27 are secured to the platform to prevent the car from leaving the platform before it is returned to its original position in the frame 18.

As soon as the rollers 21 engage the lower ends of the tracks 20, the continued reeling in of the cable 13 pulls the car over the stops 27 and off of the platform 23. The car is then free to follow the cable back to the loading area.

While we have described our elevator in connection with a wheeled car or vehicle of the drag line type, it is apparent that other types of cars or skips without wheels may be used therewith and that other modifications, substitutions, changes, additions and omissions may be made therein without departing from the spirit of our invention or the scope of the appended claim.

What we claim as new is:

- 10 An elevator for raising a car or skip of the drag line type comprising a frame, an upright member at each corner of said frame having an upwardly and forwardly sloping cam track formed therein, a car receiving platform mounted on said frame for movement longitudinally thereof, and over which the drag line extends, a series of roller carrying spindles mounted on the sides of said platform, one of said spindles projecting into each of said cam tracks whereby said 15 rollers follow said cam track as said platform is moved longitudinally of said frame, members carried by said platform for guiding the car onto the same, and spaced stops on said platform for 20 limiting forward movement of a car on said platform and for forming a guide for said drag line.
